UNITED STATES PATENT OFFICE.

FRANK H. S. HYDE, OF NEW YORK, N. Y.

DESIGN FOR A CONNECTING MEMBER FOR GARMENT-SUPPORTERS.

SPECIFICATION forming part of Design No. 33,816, dated January 1, 1901.

Application filed December 6, 1900. Serial No. 33,967. Term of patent 7 years.

To all whom it may concern:

Be it known that I, FRANK H. S. HYDE, of New York, (Brooklyn,) county of Kings, State of New York, have invented and produced a new and original Design for a Connecting Member for Garment-Supporters, of which the following is a specification, reference being had to the accompanying drawing, forming part thereof.

10 The accompanying drawing is an elevation of a connecting member, illustrating the new design.

The leading or material feature of my design is the heart-shaped body portion A,

15 with the three loops projecting therefrom, as shown. The loops each have parallel sides B and curved ends C. Narrow bands D join the body A and central portions of the inner sides B of the loops, such bands being radial with respect to the body A.

20

I claim—

The design for a connecting member for garment-supporters herein shown and described.

FRANK H. S. HYDE.
